United States Patent Office.

WILLIAM H. JONES, OF BOSTON, MASSACHUSETTS.

Letters Patent No. 79,128, dated June 23, 1868.

IMPROVED QUARTER-BOOT FOR HORSES.

The Schedule referred to in these Letters Patent and making part of the same.

TO ALL PERSONS TO WHOM THESE PRESENTS MAY COME:

Be it known that I, WILLIAM H. JONES, of Boston, in the county of Suffolk, and State of Massachusetts, have invented an Improved Quarter-Boot for Horses; and I do hereby declare the same to be fully described in the following specification, and represented in the accompanying drawings, of which—

Figure 1 is a top view,

Figure 2 a side elevation,

Figure 3 a longitudinal section, and

Figure 4 a transverse section of it.

Figure 5 is a bottom view of it.

The purpose of the boot is to prevent a horse, while trotting fast, from cutting or bruising the heels, or lower joint of the fore leg, by what is termed "overreaching" of the hoof of the hind leg.

In carrying out my invention, I form the boot, not only with a back-rest, to support it on the top of the heel, but with an internal projection, to fit into the hollow of the heel of the foot, so as to prevent the boot from turning around or rising on the hoof; and I also make the boot with one or more grooves or recesses going around it, as hereinafter described, to receive the fastening-strap, in order that the outer surface of such strap may be flush or even with that of the boot.

The groove or grooves for receiving the strap, also serve to hold the strap in place on the boot, and prevent it from being torn off the heel of the boot by the rear foot of a horse when the boot may be in use. By bringing the strap or straps flush with the outer surface of the boot, they are prevented from doing injury to the knee or leg next to the leg on which the boot may be worn.

For convenience of forming the boot, and to impart to it a proper elasticity, I mould it from India rubber or gutta percha, it being formed, generally, as shown at A, in the drawings, and with a heel-projection, a, extended from the middle of the inner surface of the heel.

The quarters I face on their inner surfaces with strips, b b, of canvas, cemented on them, in order to prevent them from being torn by the strap-rivets c c.

The fastening-strap B, as shown in the drawings, is furcated, or made with four branches, d d, e e, proceeding from the inner or heel part, f, buckles g g' being fixed to two of the said branches, e e. The other two branches, d d, are to be punctured with holes, in order that they may be buckled to the branches e e.

The boot has main and branch grooves, g' h h, made in and through its outer surface, to receive the strap and its branches, such grooves being as represented, and for the purposes hereinbefore mentioned.

The back-rest of the boot, shown at k, by resting on the upper parts of the heel of the hoof, prevents the boot from dropping off or slipping down on the hoof. The projection a, by entering the recess of the heel of the hoof, prevents the boot from rising upward, as well as from turning about on the heel. The back-rest supports the projection a in its proper place on the heel.

I do not claim a quarter-boot, as made of leather, and provided with straps in the ordinary way.

I claim the quarter-boot, as made with one or more grooves, arranged as described, in its outer surface, and especially about its heel, such being to receive the fastening-strap or straps, as set forth.

I also claim the arrangement of the fastening-strap within a groove going around the heel and through either or both the sides or quarters of the boot, in manner substantially as specified.

I also claim the boot, as made with a heel-projection, a, and the back-rest k, arranged as specified.

I also claim the arrangement of the canvas quarter-facings with the shoe and the strap-rivets, in manner as described.

WM. H. JONES.
